(57) **CLAIM**

The ornamental design for a hold down clamp for cutting and machining tables and jigs, as shown and described.

DESCRIPTION

FIG. 1 is an upper perspective view of a hold down clamp for cutting and machining tables and jigs showing my new design;

FIG. 2 is a side view thereof;

FIG. 3 is an opposite side view thereof;

FIG. 4 is a front view thereof;

FIG. 5 is a rear view thereof;

FIG. 6 is a top plan view thereof;

FIG. 7 is a bottom plan view thereof;

FIG. 8 is a bottom perspective view thereof; and,

FIG. 9 is a side view showing the hold down clamp for cutting and machining tables and jigs in a condition of use. The broken lines in FIG. 9 are directed to environment and form no part of the claimed design.
